UNITED STATES PATENT OFFICE.

EMERSON H. STRICKLER, OF NEW YORK, N. Y., ASSIGNOR TO GENERAL CHEMICAL COMPANY, OF NEW YORK, N. Y., A CORPORATION OF NEW YORK.

MANUFACTURE OF MONOALKALI-METAL PHOSPHATE.

1,150,900.

Specification of Letters Patent. Patented Aug. 24, 1915.

No Drawing.

Application filed March 23, 1912. Serial No. 685,863.

To all whom it may concern:

Be it known that I, EMERSON H. STRICKLER, a citizen of the United States, and a resident of the city of New York, State of New York, have invented certain new and useful Improvements in the Manufacture of Monoalkali-Metal Phosphate, of which the following is a specification.

My invention relates to the manufacture of mono-alkali metal phosphates, an example of which is mono-sodium phosphate which is stated to have, apart from water of crystallization, the formula NaH_2PO_4 .

An object of my invention is to provide a novel process for the production of mono-alkali metal phosphates by which a substantially pure product is capable of being obtained on a commercial scale and at a commercially reasonable cost.

Another object is to provide a cyclic process for the production of mono-alkali metal phosphate in which the residue, after the mono-alkali metal phosphate has been separated out, is introduced into an earlier stage of the complete process, such as that stage at which tri-alkali metal phosphate is made for example in accordance with the process set forth in my Letters Patent No. 744,128, dated November 17, 1903, or in my Letters Patent No. 1,037,837, dated September 3, 1912.

Other objects will be pointed out or will otherwise appear in the following description of my invention, in which, as well as in the appended claims, I use the term "alkali metal phosphate" to include the di- and tri-alkali-metallic salts of phosphoric acid, such as sodium or potassium; "di-alkali metal phosphate" to include di-sodium phosphate and di-potassium phosphate; "tri-alkali metal phosphate" to include tri-sodium phosphate and tri-potassium phosphate; "mono-alkali metal phosphate" to include mono-sodium phosphate and mono-potassium phosphate; and "acid" to include acids free from phosphorus, such as sulfuric, nitric and hydrochloric acids.

Heretofore mono-sodium phosphate has been a laboratory product only. The laboratory methods of producing it are (1) treating phosphoric acid (H_3PO_4) with sodium carbonate until the mixture is neutral, using methyl orange as an indicator; (2) treating tri-sodium phosphate or di-sodium phos-

phate with phosphoric acid; or (3) adding 55 alcohol to a solution of di-sodium phosphate in nitric acid.

For commercial and technical purposes, none of the above methods are of utility in obtaining a pure mono-sodium phosphate, 60 principally owing to the presence of impurities, such as iron, alumina fluorin and organic matter, always contained in commercial grades of phosphoric acid, which impurities are not removable therefrom by 65 commercial and technical operations and which contaminate the mono-sodium phosphate produced therefrom in accordance with the first two of the above methods, and, in the case of the third laboratory method, 70 owing to the prohibitive cost of the alcohol. On the other hand my improved process of making mono-alkali metal phosphates, which, of course, includes mono-sodium phosphate, is both a commercially available 75 process and one which results in a product commercially free from iron, alumina, and the other impurities above mentioned, a product which is only accompanied by small and for practical purposes, negligible 80 amounts of other alkali metal salts, such as, for example, sodium sulfate, sodium chloride, sodium nitrate. By proper methods of purification, such as crystallization, the amounts of such accompanying salts can be 85 reduced to any desired degree.

Broadly stated my invention consists in treating an alkali metal phosphate with an acid free from phosphorus, such as sulfuric acid, hydrochloric acid, or nitric acid, in 90 such a manner as to liberate all the phosphoric acid contained in the alkali metal phosphate, separating the phosphoric acid from the salt of the acid which has been used and treating the phosphoric acid with 95 a further amount of alkali metal phosphate in such a manner as to produce mono-alkali metal phosphate. The liquor containing phosphoric acid and the salt of the added acid is preferably treated to separate its 100 constituents by removing the salt of the added acid. It is obvious that the removal of the salt of the added acid may be effected subsequently to the final addition of alkali metal phosphate, but this method is 105 found not to be so efficient as the first mentioned process.

When the phosphoric acid is separated

from the salt of the added acid, the separated salt carries with it varying, though small, amounts of phosphoric acid or of a phosphate. The salt of the added acid thus 5 contaminated is, according to my invention, utilized in the production of tri-alkali metal phosphate, as, for example, by the process described in my Letters Patent No. 744,128 or my Letters Patent No. 1,037,837 herein- 10 before mentioned, which tri-alkali metal phosphate may be used in the present process of making mono-alkali metal phosphate. There is thus evolved a cyclic process in which all of the alkali metal products of 15 phosphoric acid are utilized. The mono-alkali metal phosphate, moreover, is produced in a substantially pure condition. In this cyclic process, a complete separation of the phosphoric acid and the salt of the 20 added acid is obviously unnecessary because in any case all of the phosphorus contained in the original phosphate is utilized.

In the practice of that example of my 25 cyclic process in which I employ sulfuric acid as the added acid and which includes the process set forth in the above Patent 744,128, tri-sodium phosphate is made by treating "rock phosphate" *i. e.* calcium phosphate with a solution of niter cake and 30 furnacing the solution thus obtained in the presence of a carbonaceous material, the tri-sodium phosphate thus made is then treated with sulfuric acid in such a manner as to produce phosphoric acid and sodium sulfate, the last mentioned constituents are 35 then separated and the sodium sulfate, carrying with it small amounts of phosphate, is then utilized, as above set forth, in the manufacture of more tri-sodium phosphate. The phosphoric acid is 40 treated with a further amount of tri-sodium phosphate to produce mono-sodium phosphate. I have described my cyclic process in which sulfuric acid is used and the sulfate of soda produced is employed in the 45 preparation of the tri-sodium phosphate. It will be understood, however, that the salts of the other added acids may by suitable modifications be employed with equally 50 successful results. If another acid than sulfuric has been used, the salt of the added acid may obviously be converted into a sulfate by treatment with sulfuric acid so that the processes hereinbefore referred to may 55 be utilized for producing tri-alkali metal phosphate. To the sodium sulfate, produced or recovered in whatever way, the proper amount of crude phosphoric acid should be added so that the proportion between the sulfur and the phosphorus in the 60 resulting mix is that prescribed in my above referred to patent.

Various methods may be used to separate the constituents of the liquor produced 65 by the treatment of alkali metal phosphate

with acid. Furthermore, the processes of my invention are susceptible of various slight changes in detail.

To illustrate the nature of my invention the following examples are given. These 70 examples are to be considered as illustrative only.

OPERATING WITH DI-SODIUM PHOSPHATE.

Crystallized di-sodium phosphate contains approximately 12 molecular proportions of water of crystallization; *i. e.* approximately 60% of water. In carrying out my new process with this product I have found it advantageous to take into account 75 the solvent action of the water so introduced into the process and in the case of an acid containing much water such as strong hydrochloric acid, weak sulfuric acid or a weak nitric acid to use even practically dehy- 80 drated di-sodium phosphate.

Tri-sodium phosphate may be used instead of di-sodium phosphate in all of the processes described for the latter, the processes and results being substantially the 90 same.

A. Using sulfuric acid as the added acid.

Example 1.

Add sulfuric acid, preferably in the form of a 98% acid to sodium phosphate crystals or solution (crystals preferred) until the mixture is neutral to methyl orange; then add a further quantity of sulfuric acid equal to that required for neutralization; boil down until a sample of the solution when filtered from the undissolved material yields a filtrate which tests 60° Bé and remove the solid by filtering or otherwise.

To the filtrate add di-sodium phosphate until it tests neutral to methyl-orange; then concentrate to 50° Bé and proceed to separate the mono-sodium phosphate by cooling and crystallizing.

B. Using hydrochloric acid as the added acid.

Example 2.

Neutralize di-sodium phosphate with hydrochloric acid using methyl orange as indicator. Then add a further quantity of hydrochloric acid equal in amount to that first added; concentrate the mixture by evaporation until a sample portion of the mixture yields a filtrate which tests 58-60° Bé. Then separate the undissolved material by filtration or otherwise. It is preferable to allow the mixture to cool before making the separation. The separated salt is principally sodium chlorid.

To the filtrate add di-sodium phosphate until it is neutral to methyl orange; allow to cool and crystallize. The crystals thus obtained are mono-sodium phosphate.

Concentrate the mother liquor by evaporation and again crystallize. The crystals are mono-sodium phosphate. The final liquors are returned to the sodium phosphate process as previously described.

C. Using nitric acid as the added acid.

Example 3.

Neutralize di-sodium phosphate with 10 nitric acid, using methyl orange as an indicator. Concentrate by evaporation until the mixture, with its suspended solids, tests 64° Bé; add an amount of concentrated nitric acid equal to that required for neutralization; cool and separate by filtering or otherwise. The separated material is largely if not wholly sodium nitrate. Concentrate the filtrate to 60° Bé by boiling; add di-sodium phosphate until the solution is neutral to methyl orange; concentrate to 55° Bé and allow to cool and crystallize. The crystals are mono-sodium phosphate.

The mother liquor may be concentrated and crystallized. The final liquors including the sodium nitrate crystals separated above are used for making sodium phosphate.

The several grades of mono-sodium phosphate obtained in all the foregoing examples 30 are, if necessary, further purified by suitable crystallization; applying the ordinary experience and rules obtaining in such practice, the mono-sodium phosphate can be freed from accompanying salts of the added acids 35 to any extent needful in commercial operation. In the preceding examples, furthermore, trisodium phosphate may be used instead of di-sodium phosphate, with correspondingly similar results, the proportions 40 of the added materials, of course, being different.

I have also found that potassium salts corresponding to the sodium salts above used can be similarly operated upon to obtain corresponding results by this, my new process.

I claim:

1. The process of making mono-alkali metal phosphate which consists in treating alkali metal phosphate with sufficient acid 60 to produce free phosphoric acid and an alkali metal salt of the added acid, separating the last mentioned salt and the phosphoric acid and treating the phosphoric acid with sufficient alkali metal phosphate to produce 65 mono-alkali metal phosphate, substantially as described.

2. The process of making mono-alkali metal phosphate which consists in treating alkali metal phosphate with sufficient acid to 60 produce free phosphoric acid and an alkali metal salt of the added acid, suitably concentrating this product to precipitate the salt of the added acid, removing the precipitated

salt from the phosphoric acid, and treating the phosphoric acid with sufficient alkali 65 metal phosphate to produce mono-alkali metal phosphate, substantially as described.

3. The cyclic process of making mono-alkali metal phosphate which consists in treating alkali metal phosphate with sufficient acid to produce free phosphoric acid, separating the last-mentioned salt and the phosphoric acid, treating the phosphoric acid with sufficient alkali metal phosphate 70 to produce mono-alkali metal phosphate, converting the separated salt of the added acid into alkali metal phosphate and utilizing the last mentioned alkali metal phosphate in a repetition of the above operations, 75 substantially as described.

4. The cyclic process of making mono-alkali metal phosphate which consists in first making tri-alkali metal phosphate by 80 treating a phosphate containing substance 85 with an acid alkali metal sulfate and furnacing the result in the presence of a carbonaceous material, then treating the tri-alkali metal phosphate, thus produced with an acid free from phosphorus to produce 90 free phosphoric acid and an alkali metal salt of the added acid, then separating the last mentioned salt and the phosphoric acid, then treating the phosphoric acid with sufficient alkali metal phosphate to produce 95 mono-alkali metal phosphate and then converting the separated salt of the added acid into acid alkali metal sulfate and utilizing the last mentioned acid alkali metal sulfate in a repetition of the above operations, sub- 100 stantially as described.

5. The cyclic process of making mono-sodium phosphate which consists in first making tri-sodium phosphate by treating a phosphate containing substance with an acid 105 sodium sulfate and furnacing the result in the presence of a carbonaceous material, then treating the tri-sodium phosphate thus produced with sufficient sulfuric acid to produce free phosphoric acid and sodium sulfate, then separating the sodium sulfate and the phosphoric acid, then treating the phosphoric acid with sufficient sodium phosphate to produce mono-sodium phosphate and then converting the sodium sulfate into 110 acid sodium sulfate and utilizing the last mentioned acid sodium sulfate in a repetition 115 of the above operations, substantially as described.

In testimony whereof, I have hereunto set 120 my hand in the presence of two subscribing witnesses.

EMERSON H. STRICKLER.
